UNITED STATES PATENT OFFICE.

CHARLES J. HENSCHEL, OF BROOKLYN, NEW YORK.

WATER-TIGHT SNAP-SWITCH OPERATING MECHANISM.

Application filed September 9, 1920. Serial No. 409,140.

To all whom it may concern:

Be it known that I, CHARLES J. HENSCHEL, a citizen of the United States, residing at Brooklyn, county of Kings, and State of 5 New York, have invented certain new and useful Improvements in Water-Tight Snap-Switch Operating Mechanisms, of which the following is a full, clear, and concise description.

10 The objects of my invention are to provide an improved water tight snap switch operating mechanism by means of which an ordinary snap switch encircled in a water tight box or shell, provided with a cover, 15 can be operated efficiently by turning the handle in one direction and remain inoperative when the handle is turned in the opposite direction, and to provide means for connecting the handle through the medium of 20 a shaft passing through a stuffing box in the water tight cover to an adjustably spring-maintained cam plate, which engages another cam plate upon the switch shaft, so that when the cover is removed for inspection, etc. of the switch, the cover cam plate 25 is removed with the cover and the switch cam plate remains in position, thus permitting removal and replacement of the cover without readjustment of the mechanism.

30 Other objects will appear more fully from the following detail description of the preferred construction and be pointed out in the claim.

Referring to the accompanying drawings: 35 Fig. 1 is a plan view of the water tight switch box;

Fig. 2 is a horizontal cross section of Fig. 1 with the snap switch and the cam plates shown in full;

40 Fig. 3 is a plan view of the device with the water tight cover removed;

Fig. 4 is a perspective view of some of the parts at the top of the snap switch;

45 Fig. 5 is an enlarged view of the handle shaft and cover cam plate; and

Fig. 6 is a view of the cover cam plate separate from the other parts.

The numeral 1 indicates a water tight shell or box which is provided with a gasket 2 and a cover 3 secured to the shell 1 at the tapped bosses 4 by means of the screws 5.

Within the shell 1 is contained the snap switch 6 of any well known make, having 55 a square portion 7 near the upper end of its

shaft 8, which terminates in a threaded portion 9, and is best shown in Fig. 4.

Upon the shaft 8 is fitted the switch cam plate 10, the cam plate being provided with a square central hole 11, to fit the square portion 7 of the shaft 8. The switch cam plate 10 is secured to the shaft 8 by the nut 12, and is provided at its outer edge with four upwardly extending cams 13 which are 60 designed to mesh with the cams 14 of the cover cam plate 15.

The cover cam plate 15 is provided with a square central hole 16, which fits loosely around the square portion 17 of the shaft 18, which extends upwardly at its cylindrical portion 19 through the stuffing box 20 and is secured at its upper end to the handle 21, to which it is fastened by the screw 22.

The lower end of the square portion 17 is bored out at 23, as shown in dotted lines in Fig. 5, to freely accommodate the threaded portion 9 of shaft 8 and nut 12, and on the outside the lower end of the square portion 17 is lightly riveted over to prevent the cover cam plate 15 from being forced 75 off by the spring 24 and to make self-contained the assembly of the cover 3 and parts 14 to 24 inclusive. The spring 24 compensates for any unevenness of adjustment occurring through compression of the gasket 2 and holds the cover cam plate 15 down in driving relation with the switch cam plate 10 when the switch handle 21 is turned in a clockwise direction according to Fig. 1, and permits the cover cam plate 15 to rise 80 against the spring, and the handle 21 to be rotated in the counter clockwise direction without operating the snap switch 6 or breaking the mechanism.

Modifications of this device may be made 85 in accordance with progress of the art and one or more of the constituent novel elements may be used or combined with one or more elements not described herein without departing from the spirit of this invention.

100 I claim:

A conventional snap switch mechanism, provided with a shaft having a square upper portion surmounted by a threaded portion and a nut thereon; special means for 105 effecting a watertight enclosure of the above switch mechanism designed to permit turning on or off from the outside by an operator and including the following factors, a cam plate mounted upon the square portion 110

and secured thereon by the nut, a water-tight case and cover for the switch, a thumb turn mounted on the outer end of a second shaft extending inwardly through a stuffing box in the cover, the second shaft being provided with a square portion at its inner end and a recess in the square portion for the upper end of the threaded portion of the shaft to effect alignment between the threaded portion and the square portion of

the second shaft, a cam provided with a square central hole and slidably mounted on the square portion of the second shaft and a spring to thrust this cam into yielding engagement with the first mentioned cam whereby the latter may be driven or remain idle according to the direction of rotation in which the thumb turn is turned by an operator. 15

CHARLES J. HENSCHEL.
